UNITED STATES PATENT OFFICE.

JULIUS ARIGI, OF MARIANSKE LAZNE, CZECHOSLOVAKIA, ASSIGNOR TO THE FIRM:
AERO, TOVÁRNA CTADEL, PRAHA-VYSOČANY, CZECHOSLOVAKIA.

COMBINED LOCK AND LATCH.

Application filed November 18, 1926, Serial No. 149,217, and in Czechoslovakia December 19, 1925.

This invention relates to a device by means of which it is possible to secure from the inside, the door fastening device of a combined lock and latch of any kind, such for instance as latch-bolts and dead-bolts, individually or both together against unauthorized opening from the outside.

The chief part of the device according to the present invention comprises a finger rotatable to an angle of 90° which in one extreme position releases the two door fastening devices, whilst in the other locks them. This finger is operated from the inside by means of a handle which is preferably arranged concentrically with the outer handle and is freely rotatable relatively to the latter to the extent of 90°. The finger is arranged so as to engage in its locking position either with a projection of the sliding latch-bolt to be locked, or with a lever pivoted to the latter. The said lever effects at the same time also the locking of the lock bolt when the device is intended for the simultaneous securing of a latch-bolt and of a dead-bolt.

In the accompanying drawing:

Figure 1 is an elevation of a combined lock and latch embodying the present invention.

Figure 2 is a sectional view substantially on the line X—X of Figure 1.

Figure 3 is a view similar to Figure 1 of a slightly modified form of the invention.

Figure 4 is a horizontal section through the latch actuating spindle.

Figure 5 is a detail section on the line M—N of Figure 3.

Figure 6 is a detail of another slight modification.

In the first construction (Figures 1 and 2) there are provided two concentrically rotatable spindles 1, 2 on which are mounted handles, and one of which 1 projects inwards, and the other 2 outwards from the door. The outer spindle 2 carries an arm 3 which engages with a recess in the sliding tail 4 of the latch-bolt A and is controlled by the action of a spring 5. The tail 4 is provided with a lug 4^a projecting downward at right angles to its direction of movement.

To the said lug is pivoted a double-armed lever 6 rotatable about a pin 7 and adjustable within the limits of the recess 6^a. At the bottom end of this lever 6 is provided a tooth 6^b with which engages a leaf spring 8

pressing against the tumblers 9 of the dead-bolt B.

On the inner end-face of the hub 3^a of the outer spindle 2 is formed an axially projecting tooth 3^b which projects into the path of the flange 1^b projecting from the hub 1^a of the inner spindle 1 and extending over 270°, so that the inner spindle 1 can rotate only to the extent of 90° relatively to the outer spindle. The flange 1^b is provided with a radial finger 1^c which, in one extreme position, is contact with the tail 4 of the latch-bolt A and in the other extreme position rests against the lug 4^a.

When the finger 1^c is in the position shown in full lines in Figure 1, the latch-bolt A can be opened from the outside or from the inside, and so long as the latch is held in the opened position, the dead-bolt B can also be opened by a key inserted through the keyhole 10. In other words as long as the latch-bolt A is in the locked position, the tumblers 9 are locked by the leaf spring 8 and the tooth 6^b of the lever 6. When the latch-bolt tail 4 is moved to the right (Figure 1) the lower end of the lever 6 will swing to the left and release the spring 8 and therefore also the tumblers 9.

When the finger 1^c is turned into the position shown in dotted lines in Figure 1, in which it rests against the lug 4^a, both the latch-bolt A and the dead-bolt B will be locked.

To preclude the possibility of an unauthorized person turning the finger 1^c into the open position from the outside by means of a suitable tool, inserted for instance through a hole made in the door, in order subsequently to open the door by means of a skeleton key, to the inner face of the door is secured the upper end of a spring blade 11 in which is provided a square hole through which extends the spindle 1. The spindle 1 is provided, close to the hub 1^a, with a circumferential groove. As long as the spring blade 11 is situated away from the door (Figure 2), the spindle 1 cannot be turned; it can be turned only after the spring blade 11 has been pressed against the door to such an extent that it is completely situated in the plane of the circumferential groove in the spindle 1.

The construction in Figures 3 to 5 differs from that just described chiefly by the finger

1^c being arranged for direct engagement with the lever 6, so that the lug 4^a can be omitted, and further by a different construction of the spindles.

5 The spindles are connected here to handles 13, 14, on prismatic projections 13^a, 14^a on which are mounted the nuts 1', 2'. One of the latter is provided with a cylindrical pin for the purpose of facilitating the assembling of the parts, the said pin fitting into a corresponding hollow or recess in the other nut. The prismatic projection 14^a has a cylindrical extension 14^b which fits into a corresponding axial recess of the inner handle 13 and is provided, close to its end, with a circumferential groove 15 with which engages a pin 16 detachably mounted in the handle 13, so that the pin 16 thus protects the two handles 13, 14 from axial movement.

20 The lever 6 and the finger 1^c are mounted in one and the same plane so that the finger 1^c can engage directly with a recess 6^c of the lever 6. The finger 1^c has an axial projection 1^d (Figure 5) which, on the finger being 25 suitably turned, strikes against the arm 3. The nut 1' of which finger 1^c is a part is provided on the circumference with two recesses 1^e arranged at 90° relatively to each other, with one of which engages the leaf spring 17 which thus secures the nut 1', together with the finger 1^c in one or the other extreme position (Figure 1). In all other details this construction agrees with that of Figures 1 and 2. The recess or slot 6^a can be provided 30 at the upper end of the lever 6, so that the pin 12, and not the pin 7, will be guided in it (Figure 3). The lever 6 can engage with its upper end with a recess 4^a of the tail 4 (Figure 6). The working is the same as in Figures 1 and 2.

40 It is obvious that the two constructions described could be used also for locking either the latch-bolt A or the dead-bolt B or their equivalents, individually.

45 What I claim and desire to secure by Letters Patent of the United States is:-

1. In a combined lock and latch, the combination of a reciprocable latch-bolt, a dead bolt, means for retracting the latch-bolt, a lever connected with the latch-bolt and preventing movement of the dead bolt when the latch-bolt is in projected position, and a manually adjustable stop adapted to prevent retraction of the latch-bolt.

50 2. In a combined lock and latch, the combination of a reciprocable latch-bolt, a dead bolt, means for retracting the latch-bolt, including a two part spindle one part of which is adapted to have a limited movement independent of the other spindle member and the latch-bolt, means connected with the latch-bolt and preventing movement of the dead-bolt when the latch-bolt is in projected position, and a stop connected to said inde-

pendently movable spindle member and adapted to be adjusted to and from a position where it will prevent retraction of the latch-bolt.

55 3. In a combined lock and latch, the combination of a reciprocable latch-bolt, a dead bolt, means for retracting the latch-bolt, a lever connected with the latch-bolt and adapted to prevent movement of the dead bolt when the latch-bolt is in projected position, and a stop connected to said independently movable spindle member and adapted to be adjusted to and from a position where it will prevent retraction of the latch-bolt.

60 4. In a combined lock and latch, the combination of a reciprocable latch-bolt, a dead bolt, means for retracting the latch-bolt, including a two part spindle, one part of the spindle being independently rotatable through an arc of approximately 90° relative to the other, means connected with the latch-bolt for preventing movement of the bolt when the dead latch-bolt is in projected position, and a stop finger carried by the independently rotatable spindle member and adapted to be moved thereby to and from position to retain the latch-bolt projected.

65 5. In a combined lock and latch, the combination of a reciprocable latch-bolt, a dead bolt, means for retracting the latch-bolt, including a two part spindle, one part of the spindle being independently rotatable for a limited distance relative to the other, means connected with the latch-bolt for preventing movement of the dead bolt when the latch-bolt is in projected position, a stop finger carried by the independently rotatable spindle member and adapted to be adjusted thereby toward and from position to retain the latch-bolt projected, and means normally preventing rotary movement of said independently movable spindle member.

70 6. In a combined lock and latch, the combination of a reciprocable latch-bolt, a dead bolt, means for retracting the latch-bolt, including a two part spindle, one part of the spindle being independently rotatable for a limited distance relative to the other, and provided with an annular recess or groove, means connected with the latch-bolt for preventing movement of the gate bolt when the latch-bolt is in projected position, a stop finger carried by the independently rotatable spindle member and adapted to be adjusted thereby toward and from position to retain the latch-bolt projected, and an arm having a polygonal shaped aperture through which the independently movable spindle member extends, said arm being movable longitudinally of the spindle member into alignment with the said recess or groove to prevent turning of the spindle member.

JULIUS ARIGI.
